MOUNTING FOR AMBLYOSCOPES

Guy A. Hunt, Butler, Pa.

Application April 22, 1935, Serial No. 17,668

7 Claims. (Cl. 88—20)

My invention relates to amblyoscopes and the like, and particularly to mountings or supports therefor.

In amblyoscope structures as commonly built, the tubes are connected to bracket plates of generally segmental form which plates are in turn pivotally connected to one another so that the tubes can be angularly adjusted with respect to one another, the instrument being held in the hands of the patient somewhat after the manner in which binoculars or opera glasses are held. In the case of patients who are being treated for crossed eyes, for example, the tubes have to be very accurately adjusted relative to one another in order to have proper positions with respect to the lines of vision, and as the instruments are of considerable weight, they are too cumbersome, especially for a child, and it is a strain on the patient to hold them and to move them into the exactly correct position.

One object of my invention is to provide a support for instruments of the character referred to, together with means for adjusting the tubes relative to the support, and relatively to one another.

Another object of my invention is to provide an improved holder for cards or transparencies employed with instruments of this character.

Some of the forms which my invention may take are shown in the accompanying drawings wherein Figure 1 is a plan view of an amblyoscope and showing the application of my invention thereto; Fig. 2 is a side view thereof; Fig. 3 is an enlarged view taken on the line III—III of Fig. 1; Fig. 4 is a sectional plan view of the structure of Fig. 3; Fig. 5 is a view taken on the line V—V of Fig. 4; Fig. 6 is a view showing a modification of the structure of Fig. 5, and Fig. 7 is a modification of the structure of Figs. 1 to 5.

Referring first to Figs. 1 to 5, the amblyoscope itself which may be of a somewhat common type, comprises a pair of sighting tubes each having a distal portion 10 and a proximal portion 11. Mirrors or reflecting plates 12 are positioned in the angles formed by the tube portions 10 and 11, so as to receive the projected images or characters. The outer end of each tube carries a bracket 13 that serves to support a lamp casing 14. The brackets 13 are provided with vertical grooves 15 that serve as slideways for transparencies such as celluloid cards 16 or the like, through which the light is transmitted, so that the images or characters on the card will be shown on the mirrors 12. The patient, by placing his eyes in front of the tube portions 11, will view the images on

the mirrors 12, as in the case of a stereoscope.

In order to adjust the tubes so that the projected images on the mirrors 12 will match or coincide with one another to a desired degree and in accordance with the angular lines of vision of a cross-eyed person, the tubes are adjustable relative to one another, and this adjustment is effected by means of two plates 17 and 18, the plate 18 being connected to one tube, and the plate 17 to the other tube.

Heretofore, the plates have been pivotally connected together near their rear edges by a bolt. Connection between the plate 17 and one of the tubes is by means of a pivot 19. An adjusting rod or bolt 20 is pivotally connected to the plate 17 and extends through a U-shaped bracket 21 upon which the pivotally-mounted tube is supported. An adjusting nut 22 is rotatably supported in the bracket 21 and has threaded engagement with the rod 20, so that when the extended portion 23 of the nut is turned, the bracket 21 will be raised or lowered, carrying with it the associated tube, whereby the tubes can also be adjusted relative to one another in vertical directions.

The members thus far described are well-known in the art and do not in themselves constitute a part of this invention. One improvement which I have incorporated in the structure shown in the drawings consists of a card ejector 25, which is shown more clearly in Figs. 3 and 5, and consists of a sheet metal plate angularly bent at its upper edge, so that the reduced ends of its horizontal portion will extend into the vertical slots or guideways 15. The depending wing-like portion 26 of the ejector plate is provided with a slot through which extends a pin 27 that is usually provided for the purpose of supporting the cards 16 at their lower edges. The plate 25 can therefore be given vertical movement with respect to the frame 13 and the pin 27, and is raised to push the cards 16 upwardly some distance from the frame, where it can be conveniently grasped by the operator and removed.

In addition to the usual pin 27, I prefer to provide additional pins 28 that will hold the plate 25 in a horizontal position. The pins 27 and 28, of course, all extend through the lower portion of the frame 13. Since the plate 25 is usually formed of light sheet metal, it may be desired to increase the weight of the same by applying a knob or ball of metal 29 thereto, so that the plate will readily return to its seat upon the pins after it has been raised.

Other features of my invention will now be de-

scribed, such features consisting of an improved supporting means, and also of means for adjusting the amblyoscope tubes in vertical and horizontal directions. The main support consists of a base plate 31 and a tubular column 32. A post 33 extends into the column 32 and is provided with a longitudinally-extending slot 34 into which the inner end of a set screw 35 extends. The set screw 35 extends through and has threaded engagement with the wall of the column 32. It will be seen that the post 33 can be set at any desired vertical position and retained there by the screw 35. A cushioning spring 36 is placed in the lower portion of the column 32 to prevent excessive jar to the instrument if the screw 35 becomes loosened to such an extent as to allow the instrument and the post to move down suddenly.

While the upper end of the post 33 could be made straight, I prefer to bend the same, as shown more clearly in Fig. 2, so that a person can more conveniently look into the instrument. The upper bent end of the post 33 extends through the plates 17 and 18, and serves as a pivot pin therefor. Nuts 37 and 38 have threaded engagement with the upper end of the post, to hold the plates 17 and 18 in place, and in some instances it may be desired to employ the nut 37 as a jam nut.

In order to adjust the tubes relative to one another about the post 33 as an axis, I provide handles 40 that are of tubular form and have elongable or telescopic engagement with guide rods 41. The guide rods 41 have ball and socket engagement with the base plate 31. This universal connection is effected by drilling holes through the base, with the upper ends of the holes of reduced diameter. The rods 41 are then pushed upwardly through the holes and the lower ends of the holes then filled to prevent the enlarged lower ends of the rods from falling out of the holes. The handles 40 have universal joint connection with clamping yokes or brackets 42 that are clamped around the amblyoscope tubes. The extremities of the clamps 42 are recessed on their inner faces to receive ball-like extensions 43 formed on the upper ends of the handles 40, thereby providing desired flexible or universal joint connection between the parts 40 and 42.

The apparatus can be placed on a table with the patient seated in front of the same, whereupon the patient may grasp the handles 40 and while looking into the tubes shift the tubes until the mirrors 12 are so positioned relative to one another that there will be proper conformation of the images in said mirrors.

By supporting the handles 40 at their upper and lower ends, the adjustments referred to can be very conveniently and easily made and without excessive binding of the movable parts upon one another.

It will be seen that if for example, the handles 40 were unsupported at their lower ends, movement of the same for the purpose of adjusting the tubes would sometimes cause a twisting action to be exerted on the tubes that would bind them in their supports.

Referring now to Fig. 6, I show another means for ejecting the cards 16 from the holder. Such means consists of a pair of plates 45 that are angularly bent at their upper ends and extend into the vertical slots 46 in the card holder. At intermediate portions, the plates 45 are pivotally supported on a pin 47 that extends through the card frame. The plates 45 are weighted as indicated at 48, and the lower ends of the slots 46

are closed in any suitable manner to prevent the weighted ends of the plates from moving too far downwardly. In order to eject a card from the slideways 46, the lower ends 49 of the plates 45 are pushed together by the fingers of the operator, thereby raising the extremities of the plates in the slots 46 and pushing the card upwardly.

Referring now to Fig. 7, I show a structure wherein handles of a different form than the handles 40 are employed but which structure may be otherwise of substantially the form shown in Figs. 1 to 5. In this arrangement, clamping yokes 51 and 52 firmly engage the amblyoscope tubes. Handles 53 and 54 are connected at their upper ends to the clamps 51 and 52, respectively.

At its lower end, the handle 53 is rigidly connected to a collar 55 that may have anti-friction bearings in its inner surface for engagement with a column 32a, so that the collar 55 may be moved freely on the column not only in a vertical direction but rotatably.

The lower end of the handle 54 is connected through a coil spring 56 with a collar 57 that is rigidly secured to the column 32a. The spring 56 will permit vertical movement of the handle 54 relative to the column, as, for example, when the post 33a is raised and lowered; and will also permit the upper end of the handle to be swung in a horizontal direction or inclined direction, when adjusting the tubes about the axis of the post 33a; and will also permit the bracket 21 to be raised or lowered for adjustment of the associated tube in vertical directions.

It is not essential that the handles 53 and 54 be connected to the column 32a, and I contemplate also the use of handles extending downwardly from the tubes in convenient positions at opposite sides of the column, where they can be readily grasped by the user and employed to effect adjustments of the tubes.

I claim as my invention:

1. A mounting for amblyoscope tubes, comprising a support, means for pivotally connecting each tube to the support, a pair of handles each of which is connected at one end to one of the tubes, and elongable connecting means joining the other end of each handle and the support and being pivotally movable on the support, which permits limited movements of the handles relative to the support.

2. A mounting for amblyoscope tubes, comprising a support, means for pivotally connecting one tube to the support, a handle connected at one end to the last-mentioned tube, and elongable connecting means joining the other end of the handle and the support and being pivotally movable on the support, which permits limited movements of said handle relative to the support.

3. A mounting for amblyoscope tubes, comprising a support, a post vertically adjustable on the support, means for connecting the tubes to said post for adjustment relative to one another about the post as an axis, a handle connected at one of its ends to one of the tubes, and elongable means joining the other end of said handle and the support and being pivotally movable on the support, which permits limited movements of the handle relative to the support in vertical and horizontal directions.

4. A mounting for amblyoscope tubes, comprising a support, means for pivotally connecting each tube to the support, a pair of handles each pivotally connected at one of its ends to one of the tubes, and a connecting device between each handle and the support, comprising a member having a tele-

scopic engagement with the handle and pivotal connection with the support.

5. A mounting for amblyoscope tubes, comprising a support, a rod having telescopic connection with the said support, means for pivotally connecting the tubes to the rod, a pair of handles each of which has a universal joint connection at its upper end with one of the tubes, and connecting devices each having universal connection at one end with the support, and at its other end having telescopic connection with one of the said handles.

6. A mounting for amblyoscope tubes, comprising a vertically-extending support, means for

pivotally connecting the inner end of each tube to an upper portion of the support, and an extensible handle device flexibly connected at its ends to the outer end of each tube and to a lower portion of the support.

7. A mounting for amblyoscope tubes, comprising a vertically-extending support, means for pivotally connecting the inner end of each tube to an upper portion of the support, on an inclined axis, and an extensible handle device flexibly connected at its ends to the outer end of each tube and to a lower portion of the support.

GUY A. HUNT.
